UNITED STATES PATENT OFFICE.

EDWARD WIARD, OF LOUISVILLE, KENTUCKY.

PLOW.

SPECIFICATION forming part of Letters Patent No. 279,469, dated June 12, 1883.

Application filed February 16, 1883. (Model.)

To all whom it may concern:

Be it known that I, EDWARD WIARD, a citizen of the United States, residing at Louisville, in the county of Jefferson and State of Kentucky, have invented a new and useful Improvement in Plows, of which the following is a specification.

My invention relates to a mold-board plow having both its handles attached to a lug which is in line, or nearly so, with the beam; and it consists, first, in a mold-board plow provided with a single lug beneath the mold-board, and cast either with the standard or upon the mold-board, so as to be in line, or nearly so, with the beam, said lug serving and being adapted for receiving the confining-pivot of both handles of the plow, and affording side bearings for the lower forward ends of the handles; second, in a mold-board plow provided with a flanged lug beneath its mold-board, and in line with (or nearly so) the beam, said lug affording side and forward end bearings for both handles of the plow, and being perforated to receive the confining pivot of bolt of said handles; and, third, in the combination, in a mold-board plow, of a single lug which is beneath the mold-board, and in line, or nearly so, with the beam, and two plow-handles pivoted to said lug and connected together where they are attached to the beam, and adjustably fastened to the beam of the plow by the same bolt by which they are connected, whereby both handles can be secured in their positions beneath the mold-board and on opposite sides of the beam by simply two bolts, and said handles can be adjusted alike upon the confining pivot-bolt of the handle-lug to suit tall or short persons.

In the accompanying drawings, Figure 1 is a broken side elevation and partial section of a plow with my invention applied thereto, the plow shown being steel-faced with a cast frog or base and standard. Fig. 2 is a broken bottom view of the same, and Fig. 3 a broken top view and partial section of the same. Fig. 4 is a detail view of the standard with its perforated and flanged handle-lug. Fig. 5 is a perspective view of a portion of a cast mold-board plow with my improved flanged lug cast directly on the under side of the mold-board, the rib-like extension of standard or stay to the frog or base of the plow shown in

Figs. 1, 2, 3, and 4 being cut away between the points R and S.

In the views of the drawings, A is the mold-board; B, the point and short landside; C, the rear continuation of the landside; D, the share attached to the point and short landside; and E, the cast frog or base of the plow, to which the parts A, B, C, and D are fastened by key and lug, as *a* and *b*, and bolts and nuts, as at *c*, *d*, and *e*, so as to be readily detached therefrom for any purpose necessary. Upon the mold-board or landside a curved-standard sustaining-plate, A', is provided, and it extends from the upper edge of the landside to the upper edge of the frog or base E of the plow, as shown. Through and from this curved portion A' a cast malleable standard, F, extends both upward and downward, as shown. This standard is formed with or secured to the frog or base E, and its upper portion passes through the beam G, and by means of the shoulder *f* below the beam and an ordinary clamping or gib and key fastening, *g*, is confined upon the beam. The lower portion of the standard below the mold-board forms what I term a "handle-lug," *h*. This portion reaches down to near the sole or base of the plowshare, and has a curvature or inclination forward corresponding very nearly with the form of the under surface of the frog or base of the plow, as shown. The width of the standard may be reduced for some distance below the mold-board, and then widened so as to give a proper side bearing for the handles of the plow, as shown; and this bearing portion *h'* may be terminated in two right-angle flanges, *j j*, as shown. The lug *h* is cast with the frog E, and united along its entire length thereto, as shown by the broken-sectioned portion of the frog and lug at R S in Fig. 1. It is not necessary to have the flanged lug and standard F united when the mold-board is cast, for the lug can be cast directly upon the under side of the mold-board in line with the beam, as shown in Fig. 5 of the drawings. To this lower widened and flanged portion, *h' j j*, both the handles H H of the plow are fastened by means of a single pivot-bolt, *k*, as shown, and their lower ends abut against the flanges *j j* in a manner to keep firm and relieve the pivot-bolt *k* of undue strain. The handles H extend back with

an upward inclination on each side of the beam G, and are perforated, and provided with perforated flanged wearing-plates m opposite the portions which bear against and connect with the beam. At points opposite these wearing-plates the beam G is provided with either several adjusting-holes, n, or, the equivalent thereof, a segmental slot concentric with the pivot-bolt k of the lug h, the beam being also provided 10 at these points with wearing-plates p, which also are perforated or slotted in the same manner as is the beam. Through the handles, plates, and beam an adjusting bolt, s, is passed, and by this means the rear portions of the 15 handles are confined in position. If the handles are to be set for a tall person, they will be inclined farther from the ground, and the bolt s will be passed through a higher hole, n, and vice versa, if they are to be set for a short person. Both handles will move together on the 20 pivot-bolt k when the holes n are substituted by a segmental slot; but to move them when holes n are adopted it will be necessary to withdraw the bolt s from one set of holes and 25 place it in another. I prefer the holes n and bolt to the slot and bolt, as a more positive set of the handles can be effected with the former.

The drawings are intended to give, in general, the form of a plow made either wholly of 30 cast metal or partly of cast metal and wrought metal. In the special construction shown by Figs. 1, 2, 3, and 4 the mold-board, point, and landside are detachable from the cast base and standard, and these parts can be replaced with 35 either cast metal or steel, while the other parts are cast in one piece, thus making the metal portion of the plow of only four pieces.

In case that part of my invention which relates specially to the lug h beneath the mold-board and nearly in line with the beam for supporting both handles is to be applied to a common cast-plow, said lug h can be cast in the same position on the under surface of the mold-board as shown in Fig. 5.

45 In ordinary cast and steel plows having mold-boards and stocked with wooden beam and handles the beam-handle is bolted to the landside-handle by two bolts extra of those used in fastening the mold-board handle to the 50 mold-board; but with my invention of the lug h, supporting both handles, half these bolts are saved and facilities afforded for removing the landside when worn out without removing the bolts by which the plow is attached to the beam and handles.

55 The construction of plow which I have shown

and described is not new further than in the particulars set forth in the statement of the nature of invention and herein claimed.

I am aware that modes of attaching handles 60 to single lugs of a plow have been devised; but some of these differ from mine in requiring a greater number of parts and bolts, and in not permitting the landside, when worn out, to be removed without removing the bolts 65 by which the plow is attached to the beam and handles. Others also differ from my invention in not allowing the landside, point, and share to be removed without removing the bolts by which the plow is attached to the 70 beam and handles; and some others differ in not permitting the mold-board, share, point, and landside to be separated without removing the bolts by which the beam and handles are attached to the plow; and all of them 75 differ from my invention in not having the lug cast with the standard or mold-board, and located centrally of the beam, or nearly so, below the mold-board, and in not providing a lug which serves as an abutment for both handles, and upon which both handles are adjustable to suit tall and short persons, in the manner hereinbefore described.

What I claim as my invention, and desire to 80 secure by Letters Patent, is—

1. The combination, with a mold-board plow, of the single perforated lug h, said lug being beneath the mold-board in line, or nearly so, with the beam, and supported by the mold-board or its frog away from and out of connection with the landside, and serving to receive 90 the pivot-bolt of both handles of the plow, substantially as described.

2. The combination, with a mold-board plow, of the single perforated lug h, having 95 flanged supports j for the lower ends of the handles, said lug being arranged and supported beneath the mold-board in line, or nearly so, with the beam and away from contact with the landside, substantially as described.

3. The combination, in a mold-board plow, of the single lug h, supported and arranged out of contact with the landside upon the under side of the mold-board, in line, or nearly so, with the beam, the adjustable handles, a 105 plow-beam, two bolts, k and s, and suitable adjusting means, as at n, substantially as and for the purpose described.

EDWARD WIARD.
